ENDLESS CHAIN CUTTING MACHINE FOR USE IN MINING COAL AND OTHER MINERALS

Oswald Floyd Lewis, near Sheffield, England, as-
signor of one-half to Newton, Chambers &
Company Limited, near Sheffield, England, a
corporation of Great Britain

Application March 7, 1938, Serial No. 194,454
In Great Britain March 12, 1937

3 Claims. (Cl. 262—33)

This invention relates to coal cutting and like
machines of the kind in which an endless cutter
chain is guided within a channel around the edge
of a jib.

5 Hitherto, in the case of such chain coal cutters,
it has been customary to form the top and bottom
plates of the jib with guide members which,
in conjunction with the jib frame, retain the tool
boxes or pick boxes in place in the jib. The
10 dimensions of the boxes are necessarily restricted
by this method of retaining the chain in the jib
and the object of the present invention is to
provide improved guiding and retaining arrangements
15 which also permit a more efficient construction
of chain and a better driving arrangement
to be used.

According to the present invention, the chain
is retained within the channel around the edge
of the jib by a retaining member projecting
20 into the interior of the pick boxes or saddles
to which the pick holders are secured. Thus
there may be inwardly projecting shoulders on
the saddles or pick boxes fitting into grooves at
the bottom of the jib channel and in this case
25 the retainer preferably consists of a T-sectioned
guide bolted to the jib frame so that the inwardly
projecting shoulders at the bottom of each saddle
can slide under the crossbar of the T.

In a modification of this arrangement, the retaining
30 means consist of projections on the side
faces of the saddles, that is those faces which
are in sliding contact with the jib plates, and
the jib plates are grooved to receive the projections
which slide within the grooves as the chain
35 moves along in the channel formed between the
jib side plates.

With either of these retaining arrangements
the saddles can be of full width between the
jib plates throughout the distance from the bottom
40 of a saddle to the pick block to which it is
attached and there is consequently a maximum
space inside each saddle between the side walls
thereof.

The links connecting the pick boxes into an
45 endless chain can therefore be made wider than
the teeth of the chain driving sprocket and there
follows from this a further feature of the invention
which consists in forming the connecting links,
50 by which the pick boxes are joined into an
endless chain, with sockets or holes
therein shaped to receive the teeth of the driving
sprocket and the idler sprocket (if provided)
at the ends of the jib. Thus the drive takes
55 place through the links of the chain and not
by the chain sprocket teeth engaging within the

pick boxes between the connecting links. The
links are preferably of arcuate shape conforming
with the peripheral curvature of the driving
sprocket and of the idler chain sprocket or radius
guide which is sometimes fitted in place of the
idler sprocket.

Another feature of the invention consists in
providing the chain with dual bases: a straight
base for the straight runs of the chain along the
jib, and a curved base to fit on the sprocket or
10 sprockets or to slide around the curved guide
at the jib end, as in some other kinds of cutter
chains there may be provided three pick sockets
in some pick blocks so that cutters or picks can
be positioned to project straight out from the
15 centre of a pick box and inclined towards both
sides so as to overcome unbalanced side pick
loads.

A construction of cutter chain incorporating
the various features of the invention is illus-
20 trated in the accompanying drawings in which:

Fig. 1 is an elevation, partly in section, of a
portion of a cutter chain.

Fig. 2 is a side elevation of Fig. 1, also showing
parts in section, along line II—II of Fig. 1.

Fig. 3 is a part sectional view showing the
chain running round a sprocket.

Fig. 4 is a part sectional view showing a pick
box guided and retained on the jib and with the
picks in position.

Fig. 5 is a section on line V—V of Fig. 2.

Fig. 6 is a sectional view corresponding to Fig.
4 but showing a modification.

The chain is built up in the usual manner
from a plurality of pick boxes joined by links and
each pick box consists of a pick-carrying block
1 welded or otherwise secured to a hollow saddle
2 having two side wings or side plates 3. Each
pick block 1 is solid and some have three sockets 4
drilled therein and broached to a suitable shape
for the reception of the picks or cutters which
are shown in place on Figs. 4 and 6, and are in-
dicated by reference numeral 5, while other
blocks (not shown) may have pairs of sockets
positioned so that the picks therein make cuts
between those made by the picks 5. Each pick
is secured in its socket by a threaded stud 6
which can be inserted into threaded holes 7
from either end of the pick block as will be
clear from Figs. 2 and 3. The saddles 2 are
joined together to form an endless chain by
links 8 which are coupled to the saddles by pivot
pins 9 secured in the saddles by spreading their
ends as indicated at 10 in Fig. 1 and each pivot
pin is preferably surrounded by a sleeve or wear-
55

ing liner 11. The length of the links 8 and the positions of the pins 9 are such that the ends of the saddles abut together and thus contribute to the transverse rigidity of the cutter chain 5 and the ends of the saddles are rounded off as indicated at 12 (Figs. 2 and 3) on a curve struck from the centre line of the pins 9 so that the saddles are kept abutting as the chain goes round the driving sprocket 13 (or round an idler 10 or the curved guide at the other end of the jib) as will be clear from Fig. 3.

The bottom edges of the side wings 3 of the saddles are made flat and bear on the bottom plate 14 of the jib guide (Fig. 4) during the straight runs of the chain, while the saddles 15 are guided in the channel formed by the projecting edges of the jib side plates 15, and by the bottom plate 14 as shown in Fig. 4.

The saddles are retained by either of the means illustrated in Figs. 4 and 6. In one arrangement (Figs. 2, 4 and 5) the bottom edges of the side wings 3 of the saddles have inwardly projecting shoulders 16 and the bottom plate 14 of the jib guide has a T-sectional retaining member 17 bolted to it by means of the countersunk-headed bolt 18. The shoulders 16 projecting inwardly from the saddles slide under the outwardly projecting shoulders 19 of the member 17. In the arrangement shown in Fig. 6, the outer faces of the saddles 3', that is the faces in sliding contact with the jib plate 15', are formed with or provided with projections 20 and the jib plates 15' are channelled as at 21 (Fig. 6) to enable the projections 20 to slide within them as the chain moves along on the jib. The projections 20 and channels 21 can be proportioned so that there is proper retention of the saddles or pick boxes without any undue weakening of the jib plates 15', and are located near the edges of the plates 15' on which the blocks bear to avoid weakening the plates where the greatest bending moment occurs (i. e., adjacent the bottom plate 14'). Neither of these alternative retaining means necessitates any reduction in the widths of the saddles and the latter can be made the maximum size available between the jib plates 15 or 15' so that there is consequently a maximum amount of space between the side wings of the saddles after allowing for a sufficient thickness of the side wings.

Owing to the space available between the side wings 3 or 3' of each saddle the links 8 can be made wider than the teeth of the driving sprocket 13 and a further feature of the invention consists in forming the links 8 with sockets or holes 22 therein shaped to receive the teeth 23 of the driving sprocket 13 at one end of the jib and the teeth of the idler sprocket (if one is fitted at the other end of the jib). Thus the drive 60 takes place through the links 8 of the cutter chain and not by the sprocket teeth 23 engaging with the pick boxes. The links 8 are of arcuate shape as shown and conform with the peripheral curvature of the driving sprocket at 65 the roots of its teeth and of the idler chain sprocket or the radius guide which is sometimes fitted in place of the idler sprocket. As the sprocket teeth 23 do not enter the saddles of the pick boxes the side wings 3 of the saddles can be connected by a cross tie 24 which has its lower face 25 concave to fit closely to the body of the sprocket wheel 13 between the roots of the teeth and to the idler sprocket or curved guide used in place of it.

75 The standard form of jib in a chain coal cutter

has at one end a driving sprocket and at the other end an idler sprocket or plain radius guide and between these ends the guide is straight and the chain should therefore have a straight base for the straight section of the jib and a radius 5 base to fit on the sprocket or sprockets or to slide round the radius guide at the jib end. The chain described is provided with such a dual base consisting of the curved member 24 within each saddle of a pick box and the curved faces 25 at the bottom of the arcuate links, and a straight base 26 at the bottom of each saddle or pick box to engage the straight portions of the jib guide between the ends of the jib. The curved member 15 or cross tie 24 prevents any pick from fouling 15 the guide or sprocket.

The three sockets 4 in some of the pick blocks 1 are arranged so that the cutters or picks 5 are positioned to project straight out from the centre of a pick box and inclined towards both sides, 20 and the use of two side picks avoids the unbalanced side pick loads when only one side pick is used and thus overcomes the twisting of the chain due to the unbalanced single side pick boxes.

The arrangement according to the invention has the advantages that larger and more robust pick boxes or cutter boxes can be used and the chain can be made stronger and more efficient and have better bearing surfaces, while by reason 30 of the fact that the driving sprocket teeth engage in the connecting links and not within the boxes, the cutters or picks can be brought lower down within the boxes as they do not have to clear the tops of the sprocket teeth.

The invention also includes the individual pick boxes having saddles adapted to fit within a jib guide channel and provided either with internally directed shoulders to project under a retaining member within the jib guide channel or with relatively narrow outwardly projecting shoulders or ribs 20, located near the pick block, for fitting into corresponding grooves in the sides of the jib guide channel, and a cutter chain, for a coal cutting or like machine, built up from 45 a plurality of such pick boxes joined together by links such as the links 8 above described.

What I claim as my invention and desire to secure by Letters Patent is:

1. In a coal-cutting or like machine, a cutter chain comprising a plurality of pick boxes, saddles formed with spaced depending wings integral with said pick boxes, connecting links projecting at their ends between the spaced wings of the saddles and pivoted thereto, a substantially U-shaped guide channel for said chain, a retaining member at the bottom of said channel and projecting between the side wings of the saddles, shoulders projecting towards each other from the opposing faces of each pair of side wings, said shoulders engaging said retaining member, said shoulders forming a flat base for each saddle, and a socket in each chain link midway between its ends and shaped to receive a driving sprocket tooth.

2. The structure of claim 1, and at least one transversely extending, concave lower surface portion connecting said wings of each saddle.

3. The structure of claim 1, retaining members extending outwardly from the sides of said wings, and cooperating grooves in the inner surfaces of the sides of said channel above the floor thereof receiving said last named retaining members.
